SIDNEY PICKER, OF NEW YORK, N. Y., ASSIGNOR TO CRYSTAL CHEMICAL COMPANY, INC., OF NEW YORK, N. Y., A CORPORATION OF NEW YORK.

CONTAINER CAP.

Application filed April 26, 1926. Serial No. 104,507.

This invention relates to improvements in caps for powder distributing containers, particularly containers for powdered materials, such as, dental powders, face powders, 5 condiments, and other dry products in powder form in which small amounts are required, and which must be kept in sealed, air-tight condition within the containers.

Up to the present time the general form of 10 caps for containers for the above stated products have been of the type where one portion of a two-part cap is rotated so that a series of openings are juxtaposed into an alignment, and the powder or condiment is 15 urged outwardly by inverting or shaking the can.

Further types of caps have provided for the relative opening and closing of the cap by movement of a plate member between a 20 series of aligned openings, which openings are normally covered, and which are uncovered upon movement of the said plate member.

Heretofore, no cap has been provided 25 wherein the distribution openings in the cap for the container can be opened by pressure, and automatically closed upon the release or cessation of said pressure.

This feature is particularly desirable 30 since it is usually the fact, that the cap when opened for use and distribution of the powder is often allowed to remain open indefinitely, due to the forgetfulness of the user, and the results are detrimental since either 35 the powder is affected by the atmospheric condition, or the powder being of a poisonous nature, or content is exposed to use by children and others not acquainted with its property. This applies to the types of cap 40 where the movable plate is rotated, reciprocated, or the cover lifted away, since a positive reverse action is required usually to bring the openings out of alignment.

It is a purpose of this invention to provide 45 for a novel form of cap for a container for powder by which powder may be urged through apertures in said cap only when pressure is applied to the locking means within said cap, which locking means being 50 controlled by pressure automatically form an air-tight closure upon the release of said pressure.

To carry this out the applicant has devised a spring pressed locking plate inter- 55 posed adjacent either single or multiple

aligned openings in a cap, whereby movement thereof either opens or closes these apertures for the distribution or retention of the powder from or within the container.

Among the objects of this invention it is 60 aimed to provide a simplified powder discharge medium within a cap formed on a container for powdered contents, whereby movement of said alignment locking means through the agency of pressure will open the 65 apertures in the cap and allow for a discharge therethrough, and where the release of said locking means is carried on independently of the operation of the pressure thereon, to wit: by automatic action of a tensed 70 spring pressure means serving to release the locking means upon cessation of the pressure applied to operate the same.

Still further it is aimed to provide an apertured flat plate slidable into and out of 75 alignment with respect to a series of openings in the cap or head member of the container, whereby movement of the same will provide for a discharge of the powdered contents through said apertures, and whereby a 80 release of pressure will automatically cause the flat plate to disalign and close the apertures, whereby discharge of further powder is prevented.

It is the purpose of this invention to pro- 85 vide for a cap or closure for containers, comprising movable and fixed sections, wherein movement of one of the sections thereof opens and closes aligned apertures for the passage therethrough of the powdered contents within the container, and which member operates against spring tension, the latter force causing the said member to close the aligned apertures and to return to its original position upon release of the pres- 90 sure previously applied thereto to open the aligned apertures.

Still further it is aimed to provide a novel 100 form of container cap comprising a stamped or pressed metal cup-shaped holder in which spring tension means are positioned, and above and adjacent to which there recipro- 105 cates a locking member, in which openings are positioned to coincide with openings in a closure top, upon the extreme movement of the locking member in one direction, and which is adapted to return to its initial position by tension developed within and the actuation of the spring member associated therewith.

Still further it is aimed to provide a simple locking mechanism for a container cap whereby the movement to which the locking member is subjected consists of a short horizontal movement within guiding means, whereby an alignment of respective apertures within the locking means and the can top means is readily produced with a minimum of movement of the alignment means 10 to either open or shut position.

Finally it is aimed to provide a novel form of container closure comprising a reciprocating locking plate member slidable within the closure top and bottom members, 15 in which the bottom member has a central aperture therein, and both the top and locking plate members have apertures therein adjacent said central aperture, which apertures are brought into and out of alignment 20 upon movement only of the locking plate member.

Figure 1 represents a type view of the container including the subject matter of this invention.

25 Figure 2 is a side elevation of the element forming the subject matter of this invention.

Figure 3 is a section along lines 3—3 of Figure 2.

30 Figure 4 is a section along lines 4—4 of Figure 3.

Figure 5 is a plan view of the sliding member in the invention.

35 Figure 6 is a section along the lines 6—6 of Figure 5.

Figure 7 is a plan view showing the lower portion of the subject matter of this invention.

40 Figure 8 is a side elevation in section along the lines 8—8 of Figure 7.

45 Figure 9 is a plan view of the spring member formed along the lines of the subject matter of this invention.

Figure 10 is a plan view partly cut out of the modification of this invention.

50 Figure 11 is a plan view of a portion of the element formed of the subject matter of this invention.

Figure 12 is a side elevation in section along the lines 12—12 of Figure 11.

55 Referring to the reference characters in the drawing, numeral 13 represents the head of a container, particularly that of a metallic container formed of tin upon which the cap member 14 forms the subject matter of this invention. This cap member consists of four portions, a head 15, a reciprocating locking member 16, a base 17, and a spring member 24.

60 Referring particularly to Figure 7, the base member 17 consists of a stamped metallic section having a central aperture 18 surrounded by a circular annular projection 19, adjacent to which there is an annular channel of non uniform width 20, which channel 65 is in the form of a depression extending

slightly below the height of member 19 shown in Figure 8. Adjacent this irregular channel 20 there is formed an irregular concentric projection 21 so that the width of the base between opposite sides of the periphery 70 of the aperture 18 in the base member 17 is equal. Upon opposing sides of the member 21 there are formed the guideways 22 and 23 which are in the form of slight depressions and the purpose of which will be later 75 described.

Referring to Figure 8 the relative locations and widths of the respective sections can be more clearly determined. Within the annular channel 20, there is adapted to be 80 actuated the spring member 24, which herein is formed in the shape of a semi-circle of bent wire one end of which 25 is fixed in an aperture within channel 20, or against the side wall 19 herein not shown, it being within the province of the inventor to vary the relative portions and structural arrangement of the said spring within the cap member. The other end member 26 is fastened to a projection 27 formed on the slidable plate 85 member 16 shown in Figure 3.

Referring to Figure 3, it can be seen that the spring member 24 is attached at its extremity 25 in a position very close to the wall of the projection 19, so that the other extremity thereof will have considerable space or play for movement within the channel or guideways 20 formed in the base. 95

Referring to Figures 3, 4, 5, and 6, the slidable plate member or locking member 16 consists of a thin metallic member having a plurality of apertures 28 therein, which apertures are disposed at a positive relationship with respect to one another. Tongues or extensions 29 and 30 are formed at the opposite extremities of this plate member, the tongue 29 being adapted to slide into the guideway 22 and the tongue 30 is adapted to slide in the guideway 23. A projection 31 at the extremity of the tongue 30 is adapted to serve as a means of applying the pressure and at the same time affording a gripping means in order to bring about the movement of the plate member 16 upon the base member 17. 100

105 Referring to Figures 2 and 4, the head member 15 comprises a flat plate member bent over to form downwardly inclined extremities 32 all about its periphery, so as to surround the outer surface 33 to the base member 17 and to enclose the same. The head member 15 has a plurality of apertures 34 therein which apertures are adapted to be in alignment with the apertures 28 of the slidable plate member 16 upon the extreme 110 movement of said slidable plate and which apertures are caused to be covered by the slidable plate member when the said plate member is returned to its original position 115 upon the expansion of the spring member 24. 120

An aperture 35 is formed on one portion of the periphery of the cap 15 through which the extension or tongue 30 of the plate member 16 is adapted to pass for reciprocation.

Upon the assembly of the device as shown in Figures 2, 3, and 4, the plate member 16 is urged from right to left by pressure against the extension 31 of the plate member which is moved against the opposing resistance of the spring member 24, the motion of this plate member being guided by the means of the guideways 22 and 23 acting in conjunction with the tongues 23 and 30 of the plate member 16. As the plate member is moved towards the left the spring member 24 is tensioned and at the same time the apertures 28 are brought into alignment with the apertures 34 of the cap at which time the condiment or powder within the container passes through the opening 18 through the apertures 28 and finally out through the apertures 34 upon the article or part to be powdered.

The amount of compression of the spring 25 and the limit of expansion of the spring are controlled by the width of the concentric depression or channel 20. Upon the release of pressure against the portion 31 of the plate member the plate is urged by the expansion of the spring member 24 acting against the projection 27 thereon, to return to its original position during which operation the apertures 28 are drawn out of alignment with respect to the apertures 34 of the 30 cap and consequently the passage of material therethrough terminated.

Referring to figures 10, 11, and 12 a modification of the device is shown wherein the base member 36 consists of a central aperture 40 37 having surrounding the same, flat projection 38. Adjacent this projection there is formed a channel member 39 similar to the channel member 20 of the structure hereinbefore described, but which channel is made 45 to be practically constant in width. An outer concentric wall 40 is formed adjacent and projecting upwardly from the outer periphery of the channel 39.

It is obvious that this base member itself 50 can be formed in the stamping operation and that the complete base may be made in a one-step operation, thus providing for the low cost of the article.

The spring member 41 is adapted to be positioned on one side only of the channel member 39 and is shown in Figure 10 as being attached to a pin 42 formed as a projection adjacent the guide member 43 extending from the wall 40 and at its other extremity 60 to a projection 44 extending downwardly and into the channel member from the side of the reciprocating plate member 45. The plate member 45 is similar to the plate member 16 shown in Figures 3 to 5 inclusive, the 65 only difference being that the tongue mem-

ber 46 therein is in the shape of a T; that is, the plate member upon being stamped provides for the tongue member 46 which is bent over on itself in the form of a T so that one portion thereof may slide into the depression 47 of the guide member 43, while the lower faces thereof may slide from the projections 48 of the guide member 43.

Though in Figures 10, 11, and 12 one spring member is provided, it is within the province of the inventor to provide for a plurality of spring members, one operable in each guideway.

The operation of this device as a modification is similar to that described in Figures 1 to 8 inclusive, this form being merely a modified form where the question of space or size of the cap is to be a minimum. As shown in the bottom of Figure 10 the head, base and plate members are positioned with respect to one another in a manner similar to that shown in Figures 1 to 8 inclusive.

It is obvious that various changes and modifications may be made to the details of construction without departing from the general spirit of the invention as set forth in the appended claims.

What I claim is:

1. A cap for containers comprising a base having an aperture disposed centrally thereof, an annular depression of varying width adjacent said aperture, an offset annular projection of varying width adjacent said annular depression, guide means on opposite sides of said projection, a plate member 95 slideable across said annular projection and having apertures therein, a cap for covering said plate member, and said base, and having a series of apertures therein, normally out of alignment with those in the plate member, a spring member in said annular depression, one end of said spring member being attached to said plate member, the other end being fixed to the base, whereby inward movement of the plate through the application of pressure thereon causes the apertures in the cap and the plate to become aligned and compresses the spring member, the resiliency of which causes outward movement of said plate upon release of pressure on the 100 plate.

2. A cap for powder containers comprising a base portion, an annular wall of varying width along the outer periphery of said base, guide members on opposite sides of said wall, an annular depression of varying width adjacent said wall, a spring member positioned within said depression having one extremity fixed therein, a plate member 120 slideable on said base portion, and guided within said guide members and means on said plate member for attaching the same to the other end of said spring, apertures disposed centrally within said plate member, a cap passing over said plate and said base member 125 130

- and having apertures therein, the apertures of said cap and plate member being normally out of alignment whereby the application of pressure to provide inward movement of said 5 plate member causes compression of said spring member and the positioning of said apertures in alignment with one another, and the resiliency of said spring member causes outward movement of said plate member 10 upon release of pressure on the plate.
3. A cap for containers comprising a base member, guide means on opposite sides of said base member, a plate slideable across said base member, a spring member having one 15 end attachable to said base member and the other to said plate member, a cap enclosing said base and said plate member, aligned apertures for said base and cap members, apertures in said plate member, said plate member being movable along said base member between the guides by pressure, whereby to compress the spring member and to open the aligned apertures in said cap and base 20 members, said spring member being adapted upon the cessation of application of pressure 25 to the plate member, through expansion, to return the plate member to its original position.
4. A closure for containers comprising a base member, guide means on opposite sides 30 of said base member, a slideable plate member positioned on said base member and having projections passing within the guide means, a cap member enclosing said base member and said slideable plate, apertures in said 35 base and cap members, apertures in said plate member, an annular channel in said base member, tension means lying in said channel and having one extremity attachable to the base member and the other extremity to the 40 slideable plate member whereby displacement of the slideable plate member causes alignment of all said apertures and compression of said spring member, said spring member upon expansion being adapted to displace 45 the slideable plate member to its original position.

SIDNEY PICKER.
